UNITED STATES PATENT OFFICE.

PAUL SHAPAC, OF TABASCO, COLORADO.

STRETCHER.

1,266,723.

Specification of Letters Patent. Patented May 21, 1918.

Application filed September 5, 1917. Serial No. 189,770.

To all whom it may concern:

Be it known that I, PAUL SHAPAC, a subject of the King of Hungary, residing at Tabasco, in the county of Las Animas and State of Colorado, have invented certain new and useful Improvements in Stretchers, of which the following is a specification.

The primary object of the invention is to provide an ambulance stretcher of the folding type, preferably formed of three sections, embodying a middle section and two end sections, with the end sections folding in opposite directions to lie adjacent to and parallel with the middle section, whereby the device when folded and out of use, as for storing or expressing, the same will utilize a minimum of space.

A further object of the invention is to provide a stretcher of the folding type consisting principally of a pair of parallel side rails braced and reinforced in a peculiar manner to present a practical rigid construction from a skeleton frame.

With the above general objects in view and others that will appear as the nature of the invention is better understood, the same consists in the novel construction, combination and arrangement of parts to be herein-after more fully described, and then claimed.

In the accompanying drawing, forming a part of this application and wherein like designating characters refer to corresponding parts throughout the several views,

Figure 1 is a side elevational view of a stretcher constructed in accordance with the present invention and in operative position. Fig. 2 is a top plan view of the same showing the permanent and detachable hinge connections between the sections.

Fig. 3 is a side elevational view of the stretcher in folded position.

Fig. 4 is a cross sectional view taken on line IV—IV of Fig. 1 showing the brace connections between the side bars.

Fig. 5 is a cross sectional view taken on line V—V of Fig. 2 showing the permanent and detachable hinge connections between the connections of the side rails, and

Fig. 6 is an inverted perspective view of one of the permanent hinge connections between adjacent sections of one of the side rails, and also illustrating the cross braces between the rails.

Briefly described, the invention consists of a stretcher embodying a pair of side bars

or rails, each rail preferably being formed of three sections, with the adjacent end sections folding in a direction opposite to the other end sections whereby the device when folded will occupy a minimum of space. Each hinge connection between the adjacent rail sections includes a permanent hinge joint at one side of the rail and a detachable hinge joint or lock at the other side of the rail whereby the sections may be locked in a substantially rigid condition when operatively arranged. The side rails are connected by a covering of flexible material, as canvas, while the same are held in rigid spaced relation by transverse brace members permanently secured thereto.

Referring more in detail to the accompanying drawing, the reference numeral 10 designates the middle sections of the side rails, having connected thereto the end sections 11. A flexible covering 12, such as canvas, is stretched over the opposite sections of the side rails 10 and 11 and secured thereto in a manner to be presently described.

The sections 10 and 11 of the side rails are connected by permanent hinged joints 13 positioned at opposite faces of the side bars so that the end sections 11 of the side bars are caused to fold in opposite direction and lie superposed on opposite sides of the middle sections 10. As clearly shown in Fig. 6, the hinges 13 embody a pair of plates 14 permanently secured as at 15 to the side rail sections 10 and 11, the plates 14 having the usual hinge pintle connection 16 as is illustrated. The sides of the rails 10 opposite to the hinges 13 are provided with detachable connecting members, the same being more clearly shown in Figs. 2 and 5, and each embodies a pair of plates 17 secured to the adjacent ends of the rail sections 10 and 11 while the adjacent edges of the plates 17 are constructed similar to a hinge joint having registering barrel portions 18, as clearly shown in Fig. 2 to receive the end of a swinging hook 19 pivotally mounted as at 20 on the adjacent side of the middle rail sections 10.

The hooks 19 are preferably formed of resilient material so that the same have a binding action with the barrel portions 18 of the hinge plates 17, thereby to secure the sections 10 and 11 in their operative arrangement as shown in Figs. 1 and 2 in a practically rigid condition.

In order to hold the side rail sections in rigidly spaced relations to each other, there

is provided a plurality of transverse braces, the middle rail sections 10 having associated therewith the relatively wide metal plate braces 21 arranged between the opposite side rail sections 10 while the ends thereof are bifurcated to provide a pair of attaching straps 22, these straps being secured to the side rail sections 10 by fastening members 23. As is clearly illustrated, the fabric portion 12 has its side edges arranged beneath the ends of the straps 22 whereby the same is permanently secured to the side rails. The end rail sections 11 are spaced and braced in a similar manner by the transverse bars 24 having their angularly bent ends 25 secured in a similar manner as at 23 to the rail sections 11, and as shown in Fig. 6 the end 25 of the bar 24 and the attaching straps 22 of the plate 21 overlie the hinge plates 14 of the hinge 13, this arrangement presenting a positive lock between the side rails as well as holding the same in permanently spaced relation.

It will be understood that in use with the stretcher that the middle section will be subject to a greater amount of weight and strain and therefore the braces 21 are made of a relatively wide material and have the ends thereof bifurcated so as to provide pairs of attaching straps so as to reinforce and strengthen the section and fasten the fabric covering permanently to the side rails.

From the above detailed description of the construction of this device, it is thought that the operation thereof is readily apparent, it being noted that in folding the stretcher from the position shown in Fig. 1 to that shown in Fig. 3, it is only necessary to remove the resilient catch hooks 19 from the members 18, whereupon the end sections 11 are permitted to fold in opposite directions to lie parallel and adjacent to the middle section 10.

While the form of the invention herein shown and described is what is believed to be the preferable embodiment thereof, it is to be understood that various changes may be made in the details of construction without departing from the spirit and scope of the invention as claimed.

What I claim as new is:—

1. An ambulance stretcher including side rails, each formed of three sections, the end sections opposing each other being hinged

to opposite sides of the middle sections and adapted to swing in opposite directions to lie substantially parallel and adjacent to the middle sections, means carried by the faces of the rail sections opposite the hinge connections for locking the sections in their operative arrangement, the said means including a pair of plates having registering barrel portions and swinging hooks carried by the middle sections adapted to have their ends received in said barrel portions.

2. An ambulance stretcher including side rails, each formed of three sections, the end sections opposing each other being hinged to opposite sides of the middle sections and adapted to swing in opposite directions to lie substantially parallel and adjacent to the middle sections, means carried by the faces of the rail sections opposite the hinge connections for locking the sections in their operative arrangement, the said means including plates having registering barrel portions and spring hooks swingingly carried by the side rails wedgingly received in said registering barrel portions.

3. A stretcher including side rails formed of foldable sections, a fabric covering for each section and transverse braces arranged between the sides of said sections having strap-shaped ends secured to the inner and outer sides of said rails to reinforce the sections and secure the fabric to the side rails.

4. A stretcher including side rails formed of foldable sections and transverse braces extending between said side rails to hold the same in spaced parallel rigid position, the ends of certain of said braces being bifurcated.

5. A stretcher including side rails formed of foldable sections and transverse braces extending between said side rails to hold the same in spaced parallel rigid position, certain of said braces being relatively wide and having bifurcated ends.

6. A stretcher including side rails formed of foldable sections and transverse braces extending between said side rails to hold the same in spaced parallel rigid position, certain of said braces being relatively wide and having bifurcated ends, the ends of all of said braces permanently straddling the side rail sections.

In testimony whereof I affix my signature.

PAUL SHAPAC.
